REFINING OF PETROLEUM HYDROCARBONS TO PRODUCE GASOLINE

Filed Jan. 10, 1940

UNITED STATES PATENT OFFICE

2,284,204

REFINING OF PETROLEUM HYDROCARBONS
TO PRODUCE GASOLINE

William T. Hancock, Long Beach, Calif.

Application January 10, 1940, Serial No. 313,224

1 Claim. (Cl. 196—96)

This invention relates to the cracking and refining of petroleum oils, and may be characterized generally as providing an improved system for initially subjecting a suitable charging stock to extensive cracking to produce a high percentage of lighter than gasoline but potential gasoline forming fractions and compounds, and then subjecting these cracked products to polymerization under conditions productive of an abnormally high yield of recoverable gasoline fractions.

In accordance with the invention, the charging stock first is subjected to cracking under high temperatures, and preferably under relatively low pressures, for the purpose of causing a high degree of dissociation or cracking of heavier than gasoline fractions, and the production of lighter than gasoline compounds capable of polymerization to form gasoline fractions of non-detonating qualities. Using the present system it is possible, because of the effectiveness of the polymerizing stage, to initially subject the hydrocarbons to more intensive cracking than would normally be desirable or economical due to excessive fixed gas losses.

After the hydrocarbons have been subjected to cracking under such conditions, the cracked vapors are polymerized by contact with catalytic material and under high pressure that will produce an abnormally high degree of polymerization of the vapors in the presence of the catalyst. Following cracking, and with or without preliminary fractionation or polymerization, the vapors are mechanically compressed to a high pressure and preferably are subjected to polymerization by contacting them with adsorptive material, as by passing the vapors through a body of adsorptive clay. Being maintained under high pressure while subjected to the action of the clay, the non-volatile constituents of the vapors undergo a high degree of polymerization, with resultant and proportionate formation of gasoline fractions. After polymerization, the vapors may be further treated or fractionated by any suitable method to condense and separately remove fractions heavier than gasoline, and to finally condense the product gasoline.

The invention will be understood to best advantage from the following detailed description of a typical system embodying the invention and illustrated diagrammatically and in flow sheet form in the accompanying drawing.

The charging stock introduced to the system through line 10 may consist of any suitable petroleum hydrocarbon or fraction thereof, capable

10 of undergoing cracking in the still 11 to a degree such that the desired relatively high yields of polymerizable and potential aromatic and other high octane rating compounds, will be formed. 15 Thus the charging stock may consist of suitable crude oil or fractions such as fuel oil, gas oil or kerosene distillate. Also the invention contemplates cracking the hydrocarbons in still 11 in either liquid or vapor phases, although in general it will be preferred to maintain cracking temperatures and pressures on a given hydrocarbon undergoing cracking, such that the cracking reactions will occur at least largely in vapor phase. In flowing from line 10 through the conventionally illustrated cracking still 11, which may be of any suitable type and design, the charging stock undergoes cracking at temperatures that may range from 900° to 1300° F., or above, depending upon the nature and composition of the charging stock, under however relatively low pressures, for example from substantially atmospheric up to around 75 lbs. per sq. in. Where in order to obtain the desired degree of cracking in still 11 it may be necessary to crack the hydrocarbons at considerably higher pressures, any desired pressure may be maintained on the oil undergoing cracking, as by a valve 12 in the outlet line 13, and the pressure then reduced to below say 75 lbs. per sq. in., beyond the valve.

20 The cracked hydrocarbons are discharged through line 13 into an enlarged separating chamber or reaction zone 14 wherein any carbon and unvaporized residue are separated from the vapors and removed from the system through line 15. The cracked vapors leaving chamber 14 25 are then subjected to compression and subsequent polymerization, either with or without first being further treated in advance of the point of compression. As illustrative, the vapors may pass directly from line 16 through line 17 to a compressor or series of compressors of a type adapted to handle high temperature vapors, and conventionally illustrated at 18, or the vapors may first be discharged through line 19 for preliminary treatment, polymerization or fractionation by any suitable means, typified by column 20. Merely as illustrative, this column 30 may contain a body of adsorptive material 21 through which the vapors undergo preliminary polymerization in flowing upwardly to the outlet 22 connecting with line 17. On the other hand, column 20 may consist of an ordinary fractionating column within which the heavier ends are 35 condensed out of the vapors. The liquid polymers or condensate, as the case may be, are removed

from the base of column 20 through line 23 to be recirculated through line 24 for cracking in still 11, or discharged to storage through line 25. Where column 20 or other similar apparatus is used, it is preferred to again subject the liquid polymers or condensate to cracking and to return the cracked products to chamber 14 in order that from a given charging stock, a maximum yield of lighter cracked hydrocarbons will be produced for conversion in the high pressure stage of the system.

The relatively low pressure vapors flowing through line 17 to the compressor, are compressed by the latter to a relatively high pressure, which ordinarily will be at least 200 pounds per sq. in. higher than the vapor pressure at the inlet side of the compressor, preferably to a pressure of around 400 lbs. to 600 lbs. per sq. in. gauge. Depending upon the characteristics of the cracked vapors and the type of catalyst employed in the polymerizing chamber, pressures in excess of those named may be used in order to obtain maximum degrees of polymerization. The compressed vapors are discharged from compressor 18 through line 26 to a polymerizing zone shown typically as a vertically extending column 27. Preferably, polymerization is at least in part induced by contacting the vapors with a suitable adsorptive material such as fuller's earth, bauxite, Murock, or Death Valley clays, employed in sufficient amount to subject the vapors to intimate and prolonged contact therewith. Accordingly, column 27 is shown to contain a body 28 of such adsorptive material extending vertically above the point of entry of the vapors a considerable distance so that the vapors have a prolonged path of flow through the clay. One or more of such columns of course may be employed, depending upon the desired time of contact and length of vapor travel through the clay. The polymerizing chamber may contain in place of or in addition to the adsorptive clay, other catalytic agents capable of promoting polymerization of the vapors. For example the clay body may contain or be impregnated with any of the metals, metallic compounds, and particularly metallic salts, known to have the property of catalyzing the reactions of polymerization.

In thus being subjected to polymerization un- 50

der high pressure, a large percentage of the higher boiling and normally uncondensable vapor fractions are converted to condensable hydrocarbons within the gasoline range. At the same time, gum-forming compounds are converted to heavy liquid polymers which drain to the bottom of the column 27, from which they may be removed from the system through line 29 or recirculated through line 30 for recracking in still 11. Polymerized vapors leaving the column through line 31 may be subjected to any desired further treatment and method of condensation or fractionation to produce the gasoline product. Merely as illustrative, the vapors are shown to be subjected to initial fractionation in column 32, from the base of which heavy condensed fractions, for example within the gas oil range, may be removed to storage through lines 33 and 34, or recirculated to the cracking still through line 35. Leaving fractionating column 32, the vapors flow through line 36 to the fractionating column 37 wherein heavier than gasoline fractions, such as hydrocarbons within the kerosene distillate range, are condensed and removed from the system through lines 38 and 39, or returned to the cracking still through line 40. The vapors in fractionating column 32 may be subjected to reflux condensation by condensate delivered to the top of the column from the base of fractionating column 37 through line 41. Cracked gasoline vapors leaving column 37 through line 42 pass through final condenser 43 and the condensed gasoline flows through line 44 to receiver 45. Fixed and uncondensable gases leave the system through the valved line 46.

I claim:

The process of refining petroleum hydrocarbons that includes, subjecting the hydrocarbons to vaporization and extensive cracking, subjecting the vapors to polymerization by contacting them with adsorptive material at relatively low pressure, separating from the vapors such polymers as will form at said low pressure, then compressing the vapors and subjecting them to polymerization in contact with adsorptive material at relatively high pressure, separating from the vapors those polymers forming at said high pressure, and finally subjecting the polymerized vapors to condensation to produce gasoline.
